(57) CLAIM

The ornamental design for a bicycle shoe, as shown and described.

DESCRIPTION

FIG. 1 is a front perspective view of a bicycle shoe showing my new design;

FIG. 2 is a top plan view thereof;

FIG. 3 is a right side view thereof;

FIG. 4 is a bottom plan view thereof;

FIG. 5 is a left side view thereof;

FIG. 6 is a front view thereof; and,

FIG. 7 is a rear view thereof.

The broken lines shown in the drawings represent portions of the bicycle shoe that form no part of the claimed design.
